UNITED STATES PATENT OFFICE.

WILLIAM B. FRANKLIN, OF HARTFORD, CONNECTICUT, ASSIGNOR TO THE
COLT'S PATENT FIRE ARMS MANUFACTURING COMPANY, OF SAME
PLACE.

MAGAZINE FIRE-ARM.

SPECIFICATION forming part of Letters Patent No. 372,531, dated November 1, 1887.

Application filed June 20, 1887. Serial No. 241,828. (No model.)

To all whom it may concern:

Be it known that I, WILLIAM B. FRANKLIN, of Hartford, in the county of Hartford and State of Connecticut, have invented new Improvements in Magazine Fire-Arms; and I do hereby declare the following, when taken in connection with accompanying drawings and the letters of reference marked thereon, to be a full, clear, and exact description of the same, and which said drawings constitute part of this specification, and represent, in—

Figure 1, a top view of the receiver portion of the arm, the magazine removed, portions broken away for convenience of illustration; 15 and showing the parts as in a position of the breech-piece closed; Fig. 2, the same view as Fig. 1, but showing the parts in the position as the breech-piece wide open; Fig. 3, a transverse section through the receiver and magazine on line $z z$, Fig. 2; Fig. 4, a top view of the receiver portion, showing the magazine as about to be engaged by the breech-piece in closing; Fig. 5, the same as Fig. 4, showing the breech-piece closed and in full engagement 20 with the magazine; Fig. 6, a transverse section through the receiver and bolt in line with the handle on line $x x$, Fig. 1; Fig. 7, a side view of the breech-piece, bolt, and hammer as removed from the arm, with the bolt and handle in the vertical position; Fig. 8, an inner 25 end view of the separator I; Fig. 9, a longitudinal central section through the breech-piece, bolt, &c.; Fig. 10, a top view and partial section of the receiver, the breech-piece removed, showing the groove in the bottom of the breech-piece recess by which the locking engagement of the breech-piece is made; Figs. 30 11, 12, 13, and 14, detached views illustrating the safety device to prevent the forward movement of the hammer except when the breech-piece is properly locked; Fig. 15, a longitudinal 35 sectional view showing the sear for engaging the hammer and dog for preventing accidental movement of the breech-piece.

40 This invention relates to an improvement in that class of fire-arms in which the breech-piece is a part of a sliding bolt provided with a handle extending radially therefrom, and by which the breech-piece is drawn backward

in opening or forced forward in closing, and in which the breech-piece is secured by imparting to the bolt a rotation by means of the said handle, and particularly to those arms of this class in which a case containing cartridges may be applied over an opening in the receiver, so that cartridges will successively fall in front of the breech-piece when in its rear or open position and be forced into the cartridge-chamber by the forward movement of the breech-piece, the preferred case or magazine being substantially that shown and described in Letters Patent No. 314,823, granted to me March 31, 1885.

The magazine is in length substantially that of the length of the cartridges to be employed, and is constructed with partitions to form a circuitous pocket in which several cartridges, side by side or parallel with each other, may be introduced and arranged upon the barrel with the opening downward, so that as one cartridge passes from the mouth of the magazine into the receiver others in the column follow by their own weight, presenting successive cartridges to the opening in the receiver as the lowest one is transferred to the barrel.

The object of the first part of my invention is to provide a separating device between the column of cartridges and the receiver, so that it is impossible for a cartridge from the magazine to pass into the receiver unless the receiver is clear or a previously-introduced cartridge has been entirely removed, whereby choking of the passage is impossible.

In my patent before referred to the magazine is constructed with a flange at its forward and rear ends adapted to engage corresponding transverse grooves at each end of the opening in the receiver, so that the flange at one end of the magazine is first introduced into the groove at one end of the opening in the receiver, and then the magazine is swung laterally to bring the flange at the other end into engagement with the groove at that end of the receiver. I find in practice that in firing the recoil has a tendency to throw the rear end of the magazine from its seat.

The object of the second part of my invention is to make a dead-lock for the magazine

when in place, and while the breech-piece is in its closed or firing position, so that by such lock not only is the magazine surely brought to its position to deliver a cartridge to the receiver, but so securely held that displacement is impossible from the act of firing.

The object of the third part of the invention is to make the engagement between the extractor and the head of the cartridge in the barrel positive, so that escape after engagement is impossible until they are completely withdrawn.

The object of the fourth part of my invention is to make an interlock between the breech-piece and the receiver independent of the handle, whereby the cam action for the final closing of the breech-piece and the first part of the opening movement for starting the cartridge may be produced in the receiver independent of the handle shoulder or lug.

The object of the fifth part of my invention is to provide a locking device which will prevent the accidental withdrawal of the breech-piece entirely from the receiver, and which locking device may be operated by an over-motion of the trigger, so that if the trigger be pulled sufficiently far backward the breech-piece may be removed, but not otherwise.

A represents the receiver, to the forward end of which the barrel B is secured in the usual manner; C, the breech-piece, which is arranged to slide longitudinally in the receiver, the bolt of which is provided with a handle, D, by which the breech-piece may be rotated, and which handle works into or from a recess, E, in the side of the receiver, so that when the breech-piece is in the closed position the handle is turned down into the recess E and the breech-piece locked, or when the handle is raised from the recess and brought into a vertical position the breech-piece may be drawn rearward for opening, the handle passing through a groove in the top of the receiver to the open position, as seen in Fig. 2. This, being a common construction of arms, does not require particular description.

Upon one side of the receiver is a projection, F, which forms an enlargement of the cartridge-receiving chamber. (See Figs. 1, 2, and 3.) To the top of this enlargement of the cartridge chamber the magazine G is attached, as seen in Figs. 3, 4, and 5, the magazine being in the form of a case, adapted to receive several cartridges parallel with each other, and so that when in place the cartridges may roll by their own weight downward to the mouth of the magazine, and the mouth of the magazine, being directly over the enlargement of the receiving chamber in the receiver, will conduct the cartridges into their proper position in the receiver, forward of the front face of the open breech-piece.

The opening or mouth of the magazine is of a shape to permit the cartridge to fall through it into the receiver; but it is necessary that the column should be supported independent

of the cartridge in the receiver or of the breech-piece, so that the breech-piece may be moved backward and forward. To this end I arrange a separator, H, in the receiver at the forward end of the receiving opening, hung upon a pivot, a, in the receiver opposite the magazine side, and so as to swing backward and forward in a horizontal plane, as from the position seen in Fig. 1 to that seen in Fig. 2. When standing in the position seen in Fig. 1, the passage into the receiver is fully open; but when the separator H is turned rearward, as seen in Fig. 2, it extends into the opening and immediately below the mouth of the magazine, 80 and so that the forward end of the lowest cartridge in the magazine will rest on the separator, as indicated in Fig. 2. At the rear end of the opening in the receiver is a second separator, I, hung in the receiver upon a pivot, b, 85 and so as to swing in a horizontal plane and in substantially the same plane as the separator H, but so that when turned backward, as seen in Fig. 1, the opening into the receiver is free, but when turned forward, as seen in Fig. 2, then the separator I extends into the opening below the lowest cartridge, and so as to support the rear end of that cartridge. The magazine-mouth is only of a size to permit the free movement of a cartridge therefrom into the opening in the receiver, as seen in Fig. 3.

The separators are operated by the breech-piece. The forward separator, H, is constructed with a rearward and inward projection, d, from its hub end, which extends into a recess, e, in the side of the breech-piece, as seen in Fig. 1. When the breech-piece is in the closed position, the breech-piece also bears against the rear side of the separator H, so as to hold the separator in the forward position when the breech-piece is closed, as seen in Fig. 1; but upon the first part of the rear movement of the breech-piece the forward end of the recess e bears against the projection d from the hub of the separator and acts as a cam thereon to turn the separator rearward into the position seen in Fig. 2, so that, one cartridge having passed from the magazine into the receiver and alongside the breech-piece, the separator H will pass above such cartridge in the receiver and immediately below the forward end of the next cartridge in the magazine. Then, as the breech-piece continues its rear movement, a shoulder, f, in the side of the breech-piece engages a corresponding shoulder, g, on the hub of the separator I, and as the breech-piece continues its movement the shoulder f acts as a cam upon the separator I and turns it forward over the rear end of the cartridge in the receiver and below the next above in the magazine, as seen in Fig. 3, so that the two separators hold the column of cartridges in the magazine suspended. As the breech-piece reaches its extreme rear position, the cartridge in the receiver then rolls into its place forward of the front face of the

breech-piece, as indicated in broken lines, Fig. 2, so that when the breech-piece is again moved forward the cartridge will be forced into its place in the barrel, in the usual manner for this class of arms. The column of cartridges in the magazine will be held suspended until, as the breech-piece approaches its closed position, it strikes the rear face of the separator H and forces it forward into its closed position, as seen in Fig. 1, and so as to leave the forward end of the first cartridge in the magazine free to drop into the receiver, and as the breech-piece approaches its closed position a second shoulder, h, on the breech-piece strikes a corresponding shoulder, i, on the hub of the separator I, and as the breech-piece completes its closing movement turns the separator I rearward into its closed position, as seen in Fig. 1, and so as to permit the rear end of the said next cartridge in the magazine to drop—that is to say, when the breech-piece is in its closed position the mouth of the magazine is open; but immediately as the breech-piece commences its rear movement the separator H is thrown outward and so as to come below the next cartridge in the magazine and separate the column from the cartridge which may have passed into the receiver, and also turns the rear separator into a like position, so that the column of cartridges in the magazine is supported while the breech-piece is open and until on its return it reaches its closed position.

As the breech-piece reaches its closed position the extractor engages the head of the cartridge which it has forced into the barrel, and so that when next the breech-piece is withdrawn the shell (or cartridge, if it be not exploded) will be withdrawn accordingly and pass rearward beside the cartridge which then lies in the receiving-chamber, and until the breech-piece has arrived at its extreme open position, when the shell will drop from its engagement with the extractor through an opening in the under side of the receiver, as in my patent hereinbefore referred to, leaving the way open for the cartridge, which has fallen into the receiver from the magazine, to come into place forward of the front face of the breech-piece and in its turn be forced into its place in the barrel.

The shoulders which operate the separators are formed in the sides of that part of the breech-piece which extends above the bolt and which moves backward and forward through the opening in the top of the receiver. The shoulders f and h, which operate the rear separator, I, are seen in Fig. 7. They are in line with the respective shoulders g i on the separator I—the shoulder h above the shoulder f. From the shoulder f a groove, l, extends rearward, and from the shoulder h a groove, m, extends forward, the two grooves forming a single groove between the two shoulders, so that the paths of the shoulders are one above the other. The shoulders g i on the separator

I are correspondingly arranged, as seen in Fig. 8.

As it is impossible that the separators can be thrown from their position supporting the column of cartridges until the breech-piece is completely closed, and so that its extractor shall have positively engaged the head of the shell or cartridge in the barrel which it has forced therein, it follows that a second cartridge cannot escape from the magazine into the receiver until the breech-piece has been so fully closed as to make engagement with the cartridge in the barrel, in doing which the separators are withdrawn from their support of the column and the lowest cartridge of the column will fall into the receiver beside the breech-piece and before the cartridge so falling can have passed to its position forward of the front face of the breech-piece. The separators are positively introduced above the lowest cartridge and below the column, so as to support the remaining column until this second cartridge shall have been forced into the barrel and positively withdrawn therefrom.

The magazine G is constructed with a flange, n, projecting from its forward end, which is adapted to pass beneath a transverse groove, r, on the receiver. The edge of the flange and the groove are of correspondingly curved shape, as indicated in broken lines, Fig. 4, so that the flange n on the front end of the magazine is first introduced beneath into its groove r, which serves as a center upon which the magazine may turn. Then a similar flange, s, on the rear end of the magazine passes into a corresponding groove, t, on the receiver at the rear end of the opening into the receiver. This is substantially the same as in my patent before referred to.

When the magazine is in proper place, its mouth stands over the opening into the receiver and in proper relative position thereto, so that the cartridges may fall from the magazine into the receiver, as before described. Owing to the interlocking character of the flange and groove at the forward end, that end is held firmly. To support the rear end, I introduce a spring-bolt, u, (see Fig. 4,) which acts as a latch to engage the magazine when in its proper position; but as this latch must present an inclined nose, so that the magazine may be removed or inserted without mechanically moving the latch, the force of the recoil frequently tends to overcome the power of the latch and throw the rear end of the magazine outward, as seen in Fig. 4, thus loosening it from its latch and rendering it liable to complete accidental displacement.

To insure the retention of the magazine in its proper position, I construct its lower edge with an inclined notch, w, at its rear end, and on the breech-piece I form or apply a corresponding hook, y. (See Fig. 4.) In Fig. 4 the magazine is represented with its rear end slightly withdrawn from its proper position;

but in such position the notch *w* stands in the path of the hook *y* on the breech-piece as the breech-piece approaches its closed position, and as the breech-piece completes its closing movement the hook *y* engages the notch *w*, interlocks therewith, and draws the magazine to place, as indicated in Fig. 5, so that when the breech-piece is closed the magazine is positively locked in its proper position for delivering cartridges, and so that the recoil can have no effect to displace it; but as the breech-piece commences its opening movement, which is produced by the turning of the handle in the usual manner, and as hereinafter described, the hook *y* withdraws from its engagement with the magazine and leaves the magazine free to be removed or replaced, as occasion may require, or to remain in its place, if sufficiently charged, until the breech-piece is again returned to its closed position, when the magazine will be relocked by the hook *y*. With this engagement there is no liability of accidentally displacing the magazine in the use of the arm, so long, at least, as the breech-piece remains in its closed position.

It will be evident that it is desirable in the use of this class of arms that the extractor should make positive engagement with the head of the cartridge, in contradistinction to simply a spring engagement, which is liable to escape from the cartridge if the cartridge offers sufficient resistance therefor. To accomplish this desirable object, I construct the extractor in the form of a V-shaped spring, *L* representing one leg of the spring and *M* the other. The extractor is introduced into a longitudinal chamber, *N*, in the breech-piece. (See Fig. 9.) Preferably, at its rear end, the extractor is provided with a stud, *O*, which rests in an elongated recess, *P*, in its chamber, so that while it prevents the extractor from being withdrawn from its chamber, it permits a certain amount of longitudinal play for the extractor.

The leg *M* takes a bearing or seat in the forward end of the extractor-chamber, but so as to leave the leg otherwise free to act as a part of the spring for the extractor. The leg *L* is constructed at its outer end with the usual bevel-nosed hook, *R*, adapted to ride over the flange of the cartridge as the breech piece approaches its closed position, its elasticity permitting it to yield in so doing, but so as to drop over the flange of the cartridge when the chamber is fully closed. As the extractor stands in its rear position, as seen in Fig. 9, the extractor is free to rise to thus ride over the head of the cartridge. The extractor leg *L* is constructed upon its under side with a downwardly and forwardly inclined or hook-shaped shoulder, *S*, and the bottom of the extractor-chamber is constructed with a correspondingly-inclined hook-shaped shoulder, *T*. The longitudinal movement of the extractor is sufficient to permit its hook-shaped shoulder *S* to engage with the corresponding shoulder, *T*, in the breech-piece, as indicated in broken lines.

If, after the extractor has made its engagement with the cartridge, the breech-piece be withdrawn and the cartridge offers any considerable resistance to leaving its place in the barrel, the extractor will be held by the cartridge, while the breech-piece will move rearward until the shoulder *T* has interlocked with the shoulder *S* on the extractor. Then, because such engagement of the extractor with the breech-piece prevents the extractor rising, it cannot escape from the head of the cartridge. Consequently the cartridge must follow the breech-piece if the breech piece continues its rear movement. After the cartridge has been fully withdrawn and escaped from the receiver, as before described, in the next advance of the breech-piece the nose of the extractor will strike the next cartridge under the force applied to the breech-piece, and the extractor will be moved rearward out of its locked position, and so that at the proper time it will be free to rise and pass over the flange of the cartridge, as before described.

In the usual construction of this class of arms the handle acts as a cam against the rear edge of the recess in the receiver, into which it turns in locking the breech-piece, and so that the handle itself is the block to resist recoil. The handle *D*, as before described, is made substantially a part of the bolt *U*, the bolt being tubular and of the usual construction to contain the hammer and mainspring, as shown. Upon the bolt, diametrically opposite the handle, is a radially-projecting lug, *V*. (See Figs. 7 and 8.) In the receiver in the bottom of the recess, through which the bolt travels in opening and closing the breech-piece, is a longitudinal groove, *W*, (see Figs. 6 and 10,) in which the lug *V* moves in the backward and forward movement of the breech-piece. At the closing position of the breech-piece the groove *W* is turned to one side and upward to form a right-angular extension, *Y*, of the groove. (See Figs. 6 and 10.) The width of this extension of the groove *Y* corresponds to the length of the lug *V* upon the under side of the bolt. The turn from the groove *W* into the extension *Y* is made of cam shape, as seen at 3, Fig. 10, against which the rear end of the lug *V* will work as the handle is turned to the locking position, and so that the lug *V*, working over this cam-shaped entrance to the extension *Y* of the groove, will operate to force the breech-piece forward to its completely-closed position, and so that the lug *V*, with the extension *Y* of the groove, will serve to resist the recoil. Then in the opening movement of the handle the lug *V* will work against the cam-shaped forward end, 4, of the groove *W* and impart to the breech-piece the first part of what is called its "starting movement." This relieves the handle and the rear end of its recess in the receiver from the great wear which is brought upon it in the usual construction.

To prevent the possibility of discharge of the hammer until the breech-piece is substan-

tially locked, I construct the hammer 5 with a forwardly-projecting arm, 6, upon its under side, (see Fig. 9,) which extends along the under surface of the bolt, and from the arm 6 is an upward projection, 7, which extends into a groove, 8, in the under side of the bolt when the bolt is in the locked position, and as seen in Fig. 12. This groove 8 is longitudinal, and so that the bolt may be drawn to full-cock or permitted to be discharged, the projection 7 working longitudinally through the groove 8 in such movement. In the bolt is a second groove, 9, parallel with the groove 8, and distant therefrom corresponding to the rotation of the bolt in opening, and so that when the bolt is turned to the position for opening the breech-piece the said groove 9 will stand in line with the projection 7 on the arm 6 of the hammer, and as seen in Fig. 11. These grooves, at their forward end, are connected by a circumferential groove, 10, and at their rear end are connected by a like circumferential groove, 11. When the hammer is in the closed position and the bolt is turned to the locked position, the projection 7 on the arm 6 stands at the forward end of the groove 8, as seen in Fig. 12, and in line with the circumferential groove 10. If, now, the bolt be turned to the unlocked position, it will bring the second groove, 9, into line with the projection 7 on the hammer. Then as the bolt with the breech-piece is forced backward in the usual manner the hammer will also be forced backward; but on the return, as the hammer comes to the cocked position, it engages the sear and will be thereby stopped, while the bolt and breech-piece will move forward, and in such forward movement the groove 9 will pass over the projection 7 from the arm 6 of the hammer until the closing position is reached, as seen in Fig. 11. Then, the hammer being so held, the bolt is turned toward the locked position. The said projection 7 then passes into the rear circumferential groove, 11, and will stand there until the bolt is completely locked, and so as to bring the groove 8 again into line with the stud 7 on the arm 6. Now, if at any time during the locking movement of the bolt the trigger should be pulled, the forward side of the groove 11, as seen in Fig. 13, will arrest the hammer and prevent its escape, and will so hold it until the bolt is brought to the completely-locked position, as seen in Fig. 12, and so that the groove 8 will come into line with the projection 7 on the hammer-arm 6. Thus it is impossible to discharge the hammer until the breech-piece is completely locked in the closed position.

To prevent the accidental withdrawal of the bolt and breech-piece, and yet permit its easy withdrawal when occasion requires, I arrange a dog, 12, (see Fig. 15,) in the receiver beneath the bolt, hung upon a pivot, 13, and extending forward therefrom, adapted to engage a notch, 14, in the breech-piece when the breech-piece is at its extreme rear position. This dog is arranged forward of the sear 16,

the sear being hung upon a pivot, 17, and so to be actuated by the trigger 18 to engage the cock-notches of the hammer in the manner.

From the hub of the sear a finger, 19, extends forward, and from the dog 12 a finger, 20, extends rearward and over the finger 19, and between the dog and sear I introduce a spring, 21, to bear upon both, the tendency of which is to force both the sear and the dog forward toward the hammer or breech-piece. The sear is free to operate under the action of the trigger, in the usual manner. If the breech-piece be drawn rearward while the trigger is free, the notch 14 will engage the dog 12 indicated in broken lines, Fig. 15, and so prevent further withdrawal after such movement is made; but if the trigger be pulled sufficiently far the finger 19 of the sear will be turned up against the finger 20 of the dog, and so as to turn the dog downward and out of possible engagement with the notch 14. Then the way is clear for the complete withdrawal of the breech-piece. This arrangement, whereby, under the action of the trigger, the removal of the breech-piece is permitted, is a great convenience.

I prefer the single spring 21 as a means for actuating both the sear and the dog; but a dependent spring may be introduced in the dog, if desired—say as indicated in broken lines, Fig. 15—and the sear provided with a usual spring, as also indicated in broken lines.

Parts of the invention which I have described, it will be evident, are applicable to single loaders.

Instead of making the inward swiveling movement of the separators positive, as described, the inward movement may be produced by a spring, (indicated in broken lines, Fig. 2,) the withdrawal or opening movement being positively produced, or the spring may be employed together with the positive movement.

It may be desirable to construct the receiver so that while the magazine remains charged cartridges may be introduced into the receiver, leaving those in the magazine in reserve. I have represented the arm, the magazine and the receiver upon the left-hand side. The opening of the receiver through which the cartridges are introduced is not of sufficient extent to permit the cartridges to be introduced at the right of the magazine while the magazine is in place. This opening at the right of the magazine may be increased by cutting away the receiver indicated by broken lines, Figs. 1, 2, 3, to a sufficient extent to permit cartridges to be introduced singly into a position in front of the front face of the breech-piece while the magazine is in place.

I claim—

1. In a magazine fire-arm in which the magazine is arranged above the receiver and is caused to open into the receiver, and in which the breech-piece moves longitudinally in the barrel in opening and closing, the receiver therewith of a separator at the

f the opening into the receiver and a ator at the rear end of the opening into eceiver, the said two separators hung pivots to swing in a horizontal plane and iately below the mouth of the magazine, e breech-piece constructed to engage said ators in both these opening and closing ments, substantially as described, and eby said separators are thrown into po below the column of cartridges in the zine in the opening movement of the h-piece and are returned from such po as the breech-piece completes its closing ment.

In a magazine fire-arm in which the mag- is arranged above the receiver and open- into the receiver, and in which the breech- is arranged to move longitudinally back- and forward in the receiver in the open- and closing movement, the combination with of a separator, H, hung at the for- end of the receiver opening, and so as wing in a horizontal plane immediately v the mouth of the magazine, the said rator constructed with a projection, d, and breech-piece with a corresponding recess, h which recess the said projection on the rator is adapted to engage as the breech- approaches its closed position, and a rator hung in the receiver at the rear end ie mouth of the magazine, the said rear rator adapted to swing in a horizontal e and immediately below the mouth of the azine, and the breech-piece and said rear rator constructed to engage with each r as the breech-piece approaches its closed tion, substantially as and for the purpose ribed.

In a magazine fire-arm in which the mag- e is arranged above the receiver and open- into the receiver, and in which the breech- e is arranged to move longitudinally back- d and forward in the receiver in the open- and closing movement, the combination ewith of the separator I, hung in the re- er at the rear of the magazine-opening immediately below the mouth of the maga- and so as to swing in a horizontal plane, said separator I constructed with indly-projecting shoulders i and g from its in different planes, and the breech-piece stuctured with shoulders f and h, corre- nding, respectively, to the shoulders i g, the breech-piece also constructed with lon- idinal grooves extending from said shoul- s h f, with a separator at the forward end he receiver, also arranged to swing in a izontal plane immediately below the mouth he magazine and adapted to engage with breech - piece as the breech - piece app- aches its extreme closed position, substan- lly as and for the purpose described.

In a magazine fire-arm in which the mag- ne is arranged above the receiver and so as open into the receiver, and in which the eech-piece moves longitudinally in line with barrel in opening and closing, the said

magazine constructed to engage the receiver at its forward end as a pivot upon which it may be turned in a horizontal plane, and a 70 seat on the receiver at the rear end of the magazine-opening to engage with the magazine, the magazine constructed with a notch, w, and the breech-piece with a corresponding hook-shaped projection, y, the said projection on 75 the breech-piece adapted to engage the notch in the magazine as the breech-piece approaches its closed position, substantially as described.

5. In a breech-loading fire-arm in which the breech-piece is moved longitudinally in open- and closing, the said breech - piece con- structed with a longitudinal chamber, N, from its forward end inward, combined with a V- shaped extractor arranged in said chamber, one leg of the V taking a bearing in said cham- ber, and the other leg of the V terminating outside the front face of the breech-piece in ex- tractor-hook shape, the said V-shaped extractor free for a limited amount of longitudinal move- ment in said chamber, the extractor-hook con- 85 structed with a hook-shaped shoulder, S, and the chamber with a corresponding shoulder, 90 T, substantially as described.

6. In a breech-loading fire-arm in which the breech-piece is made a part of a bolt and adapted to move longitudinally backward and forward in the receiver in opening and clos- ing, and which bolt is provided with a radial handle by which rotative movement may be im- panted to said bolt in locking and unlock- 95 ing said breech-piece, the said bolt constructed with a radial projection, V, and the receiver constructed with a longitudinal groove, W, with an extension, Y, therefrom, in which said groove and extension the said projection V is 100 adapted to work, and the opening of said groove into said extension constructed with cam-sur- faces 3 and 4, substantially as and for the pur- pose described.

7. In a breech-loading fire-arm in which the breech-piece is made a part of a bolt and adapted to move longitudinally backward and forward in the receiver in opening and clos- ing, and which is provided with a radial han- 110 dle by which rotative movement may be im- panted to said bolt in locking and unlock- 115 ing said breech-piece, and through which bolt the hammer is longitudinally arranged, the said bolt constructed with parallel grooves 8 9 and with circumferential connecting-grooves 10 11, 120 connecting said longitudinal grooves 8 and 9, the hammer constructed with an arm, 6, hav- ing a projection, 7, adapted to work in said grooves, substantially as described.

8. In a breech-loading fire-arm in which the breech-piece is made a part of a bolt and adapted to move longitudinally backward and forward in the receiver in opening and clos- ing, and which is provided with a radial han- 125 dle by which rotative movement may be im- panted to said bolt in locking and unlock- 130 ing said breech-piece, and through which bolt the hammer is longitudinally arranged, the com- bination therewith of a sear hung in the re-

ceiver, adapted to engage the hammer in the cocked position, and a dog hung forward of the sear, adapted to engage a corresponding notch in the breech-piece when at the extreme open position, the said sear and dog constructed with fingers projecting toward each other, and adapted to engage each other as the sear is

turned, substantially as and for the purpose described.

W. B. FRANKLIN.
